PRIMARY HORN ANTENNA FEEDING PLANAR REFLECTOR THROUGH HOLE IN FOCUSED CURVED REFLECTOR

Michael Wales, Durham, England, assignor to The Marconi Company Limited, a British company

Filed Feb. 15, 1963, Ser. No. 258,702

Claims priority, application Great Britain, Apr. 4, 1962, 12,954/62

9 Claims. (Cl. 343—761)

This invention relates to aerial systems and has for its object to provide improved and simplified wide aperture aerial systems which, when employed for transmission, will provide at the aperture a substantially parallel beam of radio energy from a localised primary source. As will be apparent later, the invention provides aerial systems which will give much the same performance as the well known Cornucopia type of radio horn but which are structurally much simpler and cheaper.

The invention will be described hereinafter with reference to transmission but, as will be obvious later, systems in accordance with this invention can equally well be used for reception. Expressions such as "localised primary radio unit" are therefore intended to include localised primary radiation sources such, for example, as a waveguide mouth which is fed from a transmitter and which may, from the practical point of view, be regarded as approximating to a point source, and localised receiver feeds such, for example, as a similar waveguide mouth feeding through a waveguide into a receiver.

According to this invention, an aerial system comprises a curved reflector, a localised primary radio unit in a hole in said reflector and a planar reflector opposite and facing said primary unit and in a plane at an angle to the curved reflector, the positioning of said planar reflector and the shapes and mutual arrangement of the two reflectors being such that radio energy following straight line paths from said primary unit to the planar reflector will be reflected thereby to the curved reflector and reflected again from the curved reflector along paths parallel to one another and to the plane of the planar reflector.

According to a feature of this invention, an aerial system comprises a reflector of paraboloidal curvature, a localised radio unit in a hole in the paraboloidal reflector, a planar reflector opposite and facing said primary unit and in a plane at an angle to the paraboloidal reflector, the distance of said planar reflector from said radio unit being at least approximately one half the distance of the focus of the paraboloid from said unit, and a pair of flat side walls which extend each between one of the two curved edges of the paraboloidal reflector and an adjacent edge of said planar reflector, the whole arrangement being such that radio energy following straight line paths from said unit to the planar reflector will be reflected thereby to the curved reflector and reflected again from the curved reflector along paths parallel to one another and to the plane of the planar reflector.

Preferably the localised primary radio unit is a small radio horn or flared waveguide mouth. Its mouth can lie in the general surface of the curved reflector but, if desired, it can be allowed to project a little beyond said surface in the direction of the planar reflector which, in this case, should be shifted in correspondence with the shift of the horn or waveguide mouth with respect to the position it would occupy were it in said curved surface.

Preferably also the axis of the localised primary radio unit is tilted a few degrees, e.g., about 6°, away from the normal to the flat reflector in the direction of the rear part of the curved reflector, i.e., in the direction

2

away from the mouth of the whole aerial system. The angle between the curved reflector and the planar reflector need not be fixed and constant but the said planar reflector may be hinged at one edge and moveable back and forth over an arc so that said angle is variable. Such an aerial system is useful, for example, in a height-finding radar.

The invention is illustrated in and further explained in connection with the drawings, in which: FIGURE 1 is a schematic side view of one embodiment; FIGURE 2 is a face view looking into the aperture of the aerial system of FIGURE 1; FIGURE 3 shows graphically results obtained experimentally with a system as illustrated by FIGURES 1 and 2; and FIGURE 4 shows a modification in which the planar reflector is hinged so as to be movable.

Referring to the drawings, 1 is a reflector in the form of a truncated sector of a paraboloid. In a centrally situated hole in the reflector 1 is a localised primary radio unit in the form of a small radio horn or flared waveguide mouth 2 (not shown in FIGURE 2). Opposite and facing the mouth 2 is a planar reflector 3. Radial side walls 4 connect the curved edges of the reflector 1 with the adjacent edges of the reflector 3. The cross indicated at 5 in FIGURE 1 represents the focus of the paraboloid. If the mouth of the horn 2 is in the curved surface of the reflector 1, the distance 2F (see FIGURE 1) should be twice the distance F. If, as illustrated, the horn mouth projects a little way in the direction of the reflector 3, the distance shown as F should be correspondingly reduced. The chain lines in FIGURE 1 represent energy paths from the horn via the reflectors 3 and 1 to form the final emergent parallel beam and are drawn on the assumption, which is near enough for practical purposes, that the mouth 2 is a point source in the surface of the reflector 1.

The arrangement of FIGURES 1 and 2, simple structurally though it is, gives good performance and gain with high aperture efficiency and low noise characteristics approximating to those of the considerably more expensive Cornucopia horn, though the bandwidth may be rather less. As will be appreciated the invention operates by the production of a virtual source (at the focus) from a real source (the mouth 2). Electrically both the real and virtual sources are well within the aperture plane of the paraboloidal sector and there is good screening from extraneous radiation (primarily back radiation) and high gain and efficiency.

In practice, the real source 2 will normally be a small horn of the order of two wavelengths aperture size and the diffraction field will be dominant. This, however, does not seriously alter conclusions drawn from considering the operation in terms of geometrical optics with a point source (real source), as is done in drawing the chain line paths of FIGURE 1, provided, of course, that a unique phase centre is preserved and the secondary aperture amplitude pattern is modified in accordance with the amplitude pattern obtained from the primary horn.

FIGURE 3 shows the aperture illumination in the vertical plane (ordinates—units of field intensity) of the aperture for the case where a beam tilt of 6° is made by the primary horn 2 towards the rear part of the surface of the paraboloid sector. This tilt is desirable for two reasons (a) the illumination in the vertical plane is optimised for maximum aperture efficiency and (b) the reflections returned from the flat reflector 3 to the primary horn aperture are reduced. The illumination in the horizontal plane is approximately the primary horn illumination in this plane, as the degree of reflector curvature is small and, as a consequence, the space attenuation is approximately constant. In FIGURE 3 the

abscissae are values of the Y (vertical) ordinate expressed in terms of F (focal length). The flat reflector 3 intercepted about 85% of the primary horn energy in the case for which FIGURE 3 was obtained.

The modification shown in FIGURE 4 will be to a large extent self-evident from the drawing. It differs from that of FIGURES 1 and 2 in that the planar reflector 3 is not fixed but is hinged at H so that it can be swung back and forth over an arc, as indicated by the double headed curved arrow. The planar reflector is shown in full lines in its central position and in dotted lines in its two extreme positions. The result of swinging the planar reflector is, of course, to swing the emergent beam up and down over an arc in the plane of the paper in FIGURE 4. Side plates (not shown in FIGURE 4) may be provided as at 4 in FIGURE 2 but, if provided they cannot of course be fixed to the side edges of the reflector 3 which swings between them with as small a clearance therefrom as is convenient to permit of swinging.

I claim:

1. An aerial system comprising a curved reflector having a predetermined focus, a localised primary radio unit in a hole in said reflector, and a planar reflector opposite and facing said primary unit and in a plane at an angle to the curved reflector, the distance of said planar reflector from said primary unit being at least approximately one-half the distance of said focus from said unit, and the shapes and mutual arrangement of the two reflectors being such that radio energy following straight line paths from said unit to the planar reflector will be reflected thereby to the curved reflector and reflected again from the curved reflector along paths parallel to one another and to the plane of the planar reflector.

2. An aerial system comprising a reflector of paraboloidal curvature, a localised radio unit in a hole in the paraboloidal reflector, a planar reflector opposite and facing said primary unit and in a plane at an angle to the paraboloidal reflector, the distance of said planar reflector from said unit being at least approximately one-half the distance of the focus of the paraboloid from said unit, and a pair of flat side walls which extend each between one of the two curved edges of the paraboloidal

reflector and an adjacent edge of said planar reflector, the whole arrangement being such that radio energy following straight line paths from said unit to the planar reflector will be reflected thereby to the curved reflector and reflected again from the curved reflector along paths parallel to one another and to the plane of the planar reflector.

3. An aerial system as claimed in claim 1 wherein the radio unit is a small radio horn.

4. An aerial system as claimed in claim 1 wherein the radio unit has a mouth lying in the general surface of the curved reflector.

5. An aerial system as claimed in claim 1 wherein the radio unit has a mouth projecting a small distance beyond the general surface of the curved reflector in the direction of the planar reflector, the position of the planar reflector being shifted in correspondence with the shift of the horn or waveguide mouth with respect to the position it would occupy were it in said curved surface.

6. An aerial system as claimed in claim 1 wherein the axis of the localised primary radio unit is tilted a few degrees away from the normal to the planar reflector in the direction of the rear part of the curved reflector.

7. An aerial system as claimed in claim 1 wherein the planar reflector is fixed.

8. An aerial system as claimed in claim 1 wherein the planar reflector is hinged so as to be movable back and forth over an arc so that its angle to the curved reflector is variable.

9. An aerial system as claimed in claim 1 wherein the radio unit is a flared waveguide mouth.
